Fig. 3

UNITED STATES PATENT OFFICE.

HAROLD A. FISHER, OF DENVER, COLORADO.

TEE BOX.

Application filed August 21, 1923. Serial No. 658,535.

This invention relates to golf course appurtenances. More specifically the invention relates to tee boxes, and has for one of its objects to provide a novel form of tee box adapted automatically to maintain the sand in proper condition.

Another object is to provide a tee box in which moisture is supplied to sand by capillary action.

10 A further object of the invention is to provide a tee box comprising a water receptacle or compartment and a sand receptacle or compartment, and in which water is automatically supplied from the former to the latter in such quantity or at such rate as to impart the proper degree of moisture to the sand. Other objects and advantages will appear as the invention is hereinafter disclosed.

20 Referring to the drawings, which illustrate what I now consider a preferred form of the invention:

Fig. 1 is an elevation, partly in section, of one form of tee box embodying the invention.

25 Fig. 2 is a plan view of the tee box shown in Fig. 1.

Fig. 3 is an elevation, partly in section and with a part of the supporting pedestal broken away, of a different form of the invention.

30 Fig. 4 is a fragmentary detail elevation looking in the direction of the arrow 4 shown in Fig. 3, showing the lid 60 partially open, and illustrating a modified form of locking means.

While the invention may assume other forms without departing from the scope of the appended claims, I have, to avoid surplusage in disclosure, illustrated but two forms of the invention, one a simple form and the other embodying additional features and advantages. The tee box illustrated in Figs. 1 and 2 comprises a water receptacle or compartment, shown in the form of a comparatively shallow basin 10, and a sand receptacle or compartment, shown in the form of a comparatively high pail 11. The sand receptacle 11 may be conveniently supported within and resting upon the bottom of the basin 10, and the latter may be conveniently supported upon a pedestal 12. The receptacle 11 is adapted to contain sand 13, say up to the level 15, and the receptacle 10 is adapted to hold water, say up to the level 16.

The two receptacles 10 and 11 are in com-

munication with each other below the water line 16 so that water is permitted to enter the sand receptacle 11 and to rise therein throughout the entire mass of the sand by 60 capillary action, but substantially no sand enters the water receptacle 10. These functions may conveniently be effected by providing the wall of the pail 11 with a plurality of perforations or holes 17, each forming a water-conveying passage but preferably not sufficiently large to permit escape of any substantial quantity of sand from the pail 11 into the basin 10.

70 I have found that a tee box constructed substantially as above described, and having its receptacles charged with sand and water respectively, is very effective in the performance of its functions. When the pail 11, containing sand, is placed into the basin 10, 75 containing water, water enters the pail through the perforations 17 and is drawn up through the entire mass of sand by capillary action and in a comparatively short time 80 moistens all of that portion of the sand above the water level 16 to a substantially even degree and to the proper degree for the making of a good tee. Furthermore, the combination of instrumentalities maintains the said mass of sand in the desired condition 85 conducive to the formation of a good tee. The water receptacle 10 also serves as a basin in which to wash golf balls to render them free from foreign matter and more readily visible. Among other satisfactory 90 materials, the receptacles 10 and 11 may be constructed of galvanized sheet or other forms of iron.

A form of invention in many respects preferable to that shown in Figs. 1 and 2, 95 is shown in Fig. 3. In this form of the invention the tee box is shown rectangular in shape, removably mounted upon a suitable stand or pedestal 112, and provided with a partition or intermediate wall 50 dividing 100 the box into a sand receptacle or compartment 111, adapted to contain sand 113, and a water receptacle or compartment 110. The sand receptacle and water receptacle are in communication with each other through one 105 or more openings or rows of openings 117 in the partition 50 and below the desired water level 116, these openings being of such size as to permit water to flow into the sand receptacle but substantially to prevent sand from entering the water receptacle from 110 the sand receptacle.

The operation of the Fig. 3 form of invention, as thus far described, is substantially the same as the form shown in Figs. 1 and 2. However, in Fig. 3 I have shown a now preferred one of various forms of means for automatically supplying water to the water receptacle 110 when the water in the latter drops below the level 116. This means is constructed substantially as follows.

- 10 A can or water reservoir 51 is mounted within the water receptacle or compartment 110, resting upon the bottom of the latter. The reservoir 51 is hermetically sealed except at the opening 52 and a filling opening, the latter being adapted to be hermetically sealed by means of a suitable removable cap 53. A handle 54 may be provided on the can 51 for raising, lowering and carrying the same. It will be noted that the outlet opening 52 is so located in the reservoir 51 that, when the latter is in the position shown in Fig. 3, the upper edge of the said opening 52 lies flush with the normal water level 116. Assuming that the reservoir 51 is filled or partially filled with water, the receptacle 111 filled with sand 113, and the water level at 116 in the receptacle 110, the operation of the form of invention shown in Fig. 3 may be briefly described as follows.
- 20 Water from the compartment 110 enters the sand compartment and by capillary action moistens the sand 113 above the water line to the desired degree. Atmospheric pressure upon the surface of the water in the compartment 110 prevents water from discharging from the reservoir 51 through the opening 52 as long as the water level in the said compartment 110 is at or above the upper edge of the said opening 52, i. e. at or above the level 116. When the water in the compartment 110 drops below the level 116, water automatically flows from the reservoir 51 through the opening 52 until the water in the compartment 110 reaches the level 116, i. e. to seal the opening 52 against the air. By virtue of these provisions the water is automatically kept at the desired level and, by providing a reservoir 51 of suitable size, the tee box is automatically supplied with water for any desired length of time.

- 30 The last described tee box is shown provided with a receptacle 55, in the form of a cup or trough, for washing the golf balls. Water is automatically kept at the level 116 in this receptacle 55 by virtue of one or more openings 56 establishing communication between the receptacles 55—110 below the water level. The provisions last described serve an additional function, i. e. to prevent the water level from rising too high. Obviously, if as the result of a leak in the upper part of the reservoir or container 51, or other cause, the water level rises above the top of the opening 52, water

will overflow the upper edge of the cup or trough 55.

The tee box last described is shown also provided with a pair of doors or lids 60, 61 hinged to the box at 62 and adapted normally to close but to permit access to the compartments 110 and 111 respectively. The door or lid 61 is provided with a portion 64 which projects beyond the side of the compartment 111 thereby facilitating opening 75 of the lid 61 and entrance of the hand into the sand compartment. In order to prevent access to the compartment 110, except by the person or persons authorized or under duty to inspect the same and to refill the reservoir 80 51, the door 60 may be provided with a hasp 65 adapted to receive a staple 66, secured to the tee box and adapted to receive a padlock 67.

In order to keep each tee box supplied 85 with water the attendant would visit the same once a week, or once a month (depending upon the capacity of the reservoir 51), unlock and open the door 60, remove the container 51, remove the cap 53, fill the container 51 with water, replace the cap 53, place the container in the compartment 110, and close and lock the lid 60.

In order to prevent inadvertent failure to close the lids 60 and 61, the box may be provided with a stop member 63 suitably secured thereto in the path of opening of the lids 60, 61 and adapted to be engaged by each of the lids before it reaches a vertical position so as to cause it to drop automatically by gravity to closed position when released.

If desirable, a snap lock may be substituted for the elements 65, 66, 67. Thus, in Fig. 4, I have shown the door 60 provided with a member 76 adapted to enter the lock 77 secured to the inner side of the wall 75 of the box and adapted to be unlocked by insertion and manipulation of the proper key in the key hole 78. When the lid 60 is released, after having been opened, it drops automatically to closed position, the member 76 automatically enters the lock 77 and locks the lid to the box. Thus, by virtue of the member 63, the lids 60, 61, are biased or urged by gravity to closed position and, by virtue of the locking devices 76, 77, the lid 60 is biased to, or automatically operated to, locked condition.

In accordance with the provisions of the 120 patent statutes, I have herein described the principles of operation of my invention, together with the apparatus which I now consider to represent the best embodiment thereof, but I desire to have it understood that 125 the apparatus disclosed is only illustrative and that the invention can be carried out by other means. Also, while it is designed to use the various features and elements in the combinations and relations described, some 130

of these may be altered without interfering with the more general results outlined, and the invention, within the scope of the appended claims, extends to such use.

5. What I claim is:

1. A tee box comprising in combination, a water receptacle, a sand receptacle in communication with said water receptacle below the water level, and means comprising a
- 10 water reservoir for automatically supplying water to said water receptacle when the water in the latter descends below a predetermined level.
- 15 2. A tee box comprising in combination, a water compartment, means for automatically preventing the water in said compartment from dropping below a predetermined level, and a sand compartment in communication with said water compartment below the
- 20 water level.
- 25 3. A tee box comprising in combination, a water receptacle, a sand receptacle in communication with said water receptacle below the normal water level, and a water reservoir in communication with said water receptacle substantially at said normal water level.
4. A tee box as specified in claim 1 and provided with a receptacle for washing

balls, the last mentioned receptacle being in 30 communication with the water receptacle below the water level.

5. A tee box as specified in claim 2 and provided with a receptacle for washing balls, the last mentioned receptacle being in communication with the water compartment below the water level. 35

6. A tee box comprising in combination, a casing having a water compartment and a sand compartment in communication with 40 each other below the water level, a plurality of doors for permitting access to said compartments, and means for causing each of said doors to close when released.

7. A tee box comprising in combination, a normally inaccessible water receptacle, a sand receptacle in communication with said water receptacle below the water level and extending upwardly whereby the sand to be used in making the tees is above the level of 45 the water in the water receptacle, and a second water receptacle in communication with said first mentioned receptacle and in which golf balls may be immersed and washed. 50

In testimony whereof I hereunto affix my 55 signature.

HAROLD A. FISHER.
